UNITED STATES PATENT OFFICE.

THEODORE F. KOTTER, OF HOLLIS, NEW YORK, ASSIGNOR TO TED MORTON CO. INC.,
OF NEW YORK, N. Y., A CORPORATION OF NEW YORK.

DESIGN FOR AN ANIMAL DOLL.

Application filed February 28, 1923. Serial No. 5,311. Term of patent 3½ years.

To all whom it may concern:

Be it known that I, THEODORE F. KOTTER, a citizen of the United States, residing at Hollis, Long Island, New York, have invented a new, original, and ornamental Design for an Animal Doll, of which the following is a specification, reference being had to the accompanying drawing, forming a part thereof.

The figure of the drawing is a view in front elevation of an animal doll intended to represent a rabbit wearing a waist with cuffs thereon above which is an apron with

patch pockets thereon, the apron having an ornamenting border thereon, the apron, the border, the patch pockets, the shirt waist, the cuffs, the eyes, the nostrils and the feet all being contrastingly colored so as to produce a highly pleasing and ornamental effect.

I claim—

The ornamental design for an animal doll as shown described above.

In witness whereof I have hereunto signed my name this 21st day of February 1923.

THEODORE F. KOTTER.
